UNITED STATES PATENT OFFICE.

FRED W. TAYLOR, OF WEBSTER, MASSACHUSETTS.

SKATE-SHARPENING DEVICE.

SPECIFICATION forming part of Letters Patent No. 527,350, dated October 9, 1894.

Application filed February 5, 1894. Serial No. 499,215. (No model.)

To all whom it may concern:

Be it known that I, FRED W. TAYLOR, a citizen of the United States, residing at Webster, in the county of Worcester and State of Massachusetts, have invented a new and useful Device for the Purpose of Sharpening Ice-Skates, (which has not been patented in any country to my knowledge,) of which the following is a specification.

10 My invention relates to an improved device for the purpose of sharpening ice skates, which is made in six parts or pieces, viz: two pieces of steel about five inches long and an inch and a half or two wide, and a small 15 file about four inches long by three quarters wide, (a file either rounding or flat can be used as preferred,) and three screws, or screw bolts, to hold the device together and also to widen or narrow the sharpener upon the 20 skate blade. The two halves are of a proper thickness when joined together to fit snugly, but not tightly, upon a skate blade, and are deeply grooved upon the inner side of each half or part to hold the file.

25 The object of the invention is to provide a small, useful and handy device for the sharpening of ice skates that can be used by both old and young at any time or place.

The following is a description of the accompanying drawings.

30 Figure 1 shows an inner view of one half of the sharpener without the file. Fig. 2 is a perspective view of the complete device; Fig. 3, a perspective view of the file. Fig. 4 is a 35 view showing retaining screw engaging the file transversely at the end of the device holding it in place.

Similar letters refer to similar parts in each view.

40 The sharpener is composed of two iron or steel plates M, M, as shown in Figs. 1 and 2, so shaped as to fit upon a skate blade closely and to hold a file F, shown in Fig. 3, level and true upon the bottom of the skate run-

ner. Upon the inner side of plates M, M, are 45 grooves as shown by G, in Fig. 1, to hold the file F, Fig. 3. The file is inserted in the end of the sharpener at t which is the end of groove G, Fig. 1, and held in by screw d, shown in Fig. 2. The three screw bolts N, 50 N, and d, serve to hold the plates M, M, together and also for the purpose of contracting or expanding the sharpener to fit any thickness of skate blade. Screw d, Fig. 2, also serves to prevent the file F, Fig. 3, slipping out of the groove G, at the end of the sharpener at A, Fig. 1.

The screws N, N, and d, in Fig. 2, are to be unscrewed or screwed up as required to cause the device to fit any thickness of skate blade. 60 The two flanges H, H, in Figs. 1 and 2, serve as holders to keep file F, Fig. 3, level on the bottom of the skate runner so the skate will be sharpened level and true and keep the sharpener from inclining to either side of the 65 blade.

To use the sharpener, screw up the screws N, N, and d, as shown in Fig. 2, until flanges H, H, Figs. 1 and 2, fit snugly against the sides of the skate blade but loosely enough 70 to allow the sharpener to slide on the skate blade and then rub the sharpener from heel to toe upon the skate blade until the latter is sharp.

What I claim as my invention, and desire 75 to secure by Letters Patent, is—

The combination in a skate sharpener of two side plates M, provided with flanges H, and grooves arranged to lie opposite each other, a file seated in these grooves, a retaining screw engaging the file transversely at the end holding it in place, means for adjustably clamping the side plates together, all combined as set forth.

FRED W. TAYLOR.
